ABSTRACT OF THE DISCLOSURE

A brace device for a door, particularly of the upwardly acting type having a plurality of horizontally hinged sections, wherein brace members are secured to and project from the internal surfaces of said sections in vertical alignment. A flexible brace element, which is anchored at its upper end to a portion of the building above the door and is releasably secured at its lower end to the floor adjacent the door opening, extends along and firmly engages the projecting edges of the brace members.

BACKGROUND OF THE INVENTION

This invention relates in general to an upwardly acting door assembly having a plurality of horizontally hinged door sections and, more particularly, to a brace device or structure for resisting forces applied to the external side of the door.

The performance and construction of upwardly acting doors having horizontally hinged sections have been well known and highly developed over a considerable period of time. However, these doors are sometimes exposed to excessive forces in certain areas of the country, and the problems resulting therefrom have defied satisfactory solutions. More specifically, unusually high winds frequently develop in the seaboard states, and upwardly acting door structures, which are easily able to withstand normal stresses, are often damaged by such winds.

Upwardly acting doors are normally of lightweight construction, to facilitate their operation and because heavy materials are usually unnecessary. For example, the door sections may be made of lightweight plywood, fiberglass, aluminum or glass supported in metal frames and mounted on a pair of relatively lightweight tracks by means of a limited number of small rollers. Although such lightweight construction is highly advantageous during normal use and operation of the door, even in adverse weather conditions, such doors can be damaged by extreme winds, such as those developed during hurricanes. Furthermore, where such doors are horizontally hinged and relatively wide, they are especially susceptible to the destructive force of high winds.

Previously, in an attempt to overcome these problems, each section was reinforced by horizontal brace bars, which are often applied just before the storm occurs. Although this has reduced somewhat the amount of wind damage to such doors, it has not proven to be satisfactory since a trained person must be present to install the bars, and such installation requires a considerable period of time. If the beams are of sufficient size to provide the required strength and are permanently installed, then they add appreciably to the weight and cost of the door and its support, and the door is more difficult to open. Moreover, such bracing does not avoid the force exerted indirectly by the wind upon the tracks.

Accordingly, an object of this invention is the provision of an improved brace device, especially for a horizontally hinged and upwardly acting door, wherein sufficient reinforcement is provided to minimize damage of the type presently experienced from forces such as hurricane

2

winds, applied to the exterior of the door, and yet does not increase the weight of the door and does not obstruct the door opening when the door is in the open position.

A further object of this invention is the provision of a brace device, as aforesaid, wherein the forces exerted on the door are transferred directly to the structure of the building above and below the door.

Another object of this invention is the provision of a brace device, as aforesaid, capable of adaptation to door sections of various lengths and widths, and wherein any number of brace devices may be employed without appreciably adding to the weight of the door.

Other objects and purposes of the invention will become apparent to persons familiar with door constructions upon reading the following descriptive material and examining the accompanying drawings, in which:

FIG. 1 is a broken view of the interior side of an upwardly acting door assembly having the brace device of the present invention.

FIG. 2 is a sectional view taken along the line II—II in FIG. 1.

FIG. 3 is a broken fragment of an upwardly acting door structure equipment with a modified brace device.

For convenience in description, the terms "upper," "lower," "front," "rear" and words of similar import will have reference to the door construction embodying the invention as appearing in FIG. 2, the rear or interior side of the door being rightwardly therein.

SUMMARY OF THE INVENTION

The objects and purposes of the invention, including those set forth above, have been met by providing an upwardly acting door construction having a plurality of similar, horizontally hinged door sections, each of which has at least one rearwardly extending, horizontal brace member mounted on the interior side thereof. An upper anchor is secured to the inner side of the interior side of the wall above the door opening and a lower anchor is mounted in the floor of the building below the door opening. A flexible brace element is connected at one end to the upper anchor and is releasably engageable at the other end to the lower anchor. The flexible brace element extends vertically across the interior or rear edges of the horizontal brace members. The flexible brace element may be released from the lower anchor, when not in use, and secured to a second upper anchor for storage.

DETAILED DESCRIPTION

The upwardly acting door structure 10, one embodiment of which is shown in FIG. 1, is comprised of a plurality of similar, horizontally hinged sections 11, 11A, 11B and 11C. Corresponding parts of the sections 11A, 11B and 11C will be identified by the same numerals as their counterparts in section 11 with appropriate suffixes A, B or C. Section 11, for example, has a rectangular frame 12 constructed of wood. The frame 12 supports a plurality of panels 13 of lightweight plywood or glass. Although section 11 is shown as being constructed of wood, alternatively it could be constructed of aluminum or steel-supporting fiberglass panels or glass window panes.

The section 11 (FIG. 1) is hingedly connected to the adjoining section 11A by a hinge assembly 16, which may be of any conventional type. The sections 11, 11A, 11B and 11C are mounted on and between tracks 17 and 18 by roller assemblies 19, 21 and 22 for movement between a substantially vertical or closed position and a substantially horizontal or open position.

A horizontal brace member 23 is secured to the interior side of, and extends lengthwise of, the section 11, preferably from one end to the other thereof. The brace member 23 has a channel-shaped portion with a pair of side-

wardly projecting, coplanar flanges which are secured to the frame 12 by screws or bolts 24. The member 23 may be constructed of light gauge aluminum, steel or fiberglass. Each of the remaining sections 11A, 11B and 11C has similar, corresponding brace members 23A, 23B and 23C.

An upper anchor 27, which may be an eyebolt, is attached to the lintel or header 28 above the door opening 14 in the building by threaded engagement with the receptacle 29. A lower anchor 31, which may be similar to the anchor 27, is secured in the receptacle 32 in the floor 33 at the bottom of the door opening 14.

A flexible brace element 36 has a hook 37 at its upper end for engagement with the eyebolt 27 and a second hook 38 at its lower end for engagement with the eyebolt 31. The flexible element 36 may be constructed of wire cable or chain and should be of such length that it engages the horizontal brace members, such as the members 23 and 23C (FIG. 2), when the hook 38 engages the eyebolt 31. Yet the element 36 must be loose enough to permit engagement and disengagement of the hook 38 with eyebolt 31.

As shown in FIG. 2, the hooks 37 and 38 of cable 36 preferably engage the respective eyebolts 27 and 31 at points forwardly of the interior or rearward edges of the brace members 23, 23A, 23B and 23C, thereby minimizing rearward movement of the door 11.

An additional eyebolt 34 may be secured to the internal surface of the header 28 and spaced horizontally from eyebolt 27 about the same distance as the eyebolt 31. Thus, the hook 38 can be connected to eyebolt 34 to support the element 36 in storage position 36A when it is not in use.

Although FIG. 1 shows only one flexible brace element 36, it may be desirable, particularly for doors of greater width, to provide more than one brace element, thereby distributing the effects of wind force more uniformly on the door.

An alternate construction is illustrated in FIG. 3, wherein the upwardly acting door 40 includes a plurality of horizontally hinged sections, such as 41 and 41A, each of which is provided with a plurality of short, horizontally aligned brace members, such as 42 and 42A. A flexible brace element 43, which may be identical in construction with the brace element 36 is anchored at one end on the header 44 and releasably connected at the other end to the floor 46. It has been found that a horizontal brace member 42 as short as 4 inches functions satisfactorily when used together with the vertical flexible bracing element 43. This arrangement is especially advantageous where several elements 43 are used.

OPERATION

Although the operation of the structure embodying the invention will be apparent to skilled persons from the foregoing description, a summary thereof will now be set forth for convenience.

The door 10, when in normal operation, is opened by lifting same upwardly and thereby causing the rollers in roller assemblies 19, 21 and 22 to move along the tracks 17 and 18 in a conventional manner. The flexible brace element 36 is normally stored in an inoperative position, such as horizontally at 36A in FIG. 1.

The door 10 is closed when a hurricane warning is sounded. The hook 38 is removed from eyebolt 34 and the flexible brace element 36 is pulled downwardly against the horizontal brace members 23 and 23C until the hook 38 can be connected to eyebolt 31.

The force of the wind against the door is thus transferred directly through the cable 36 to the header 28 and the floor 33 of the building, rather than being borne by the roller assemblies 19, 21 and 22 and the tracks 17 and 18. Also each of the sections 11, 11A, 11B and 11C is held in a braced condition which avoids damage to the door.

If the building is to be unoccupied for an extended period of time, it may be desirable to place the brace ele-

ment 36 in the vertical, operative position with hook 38 being secured in eyebolt 31. The brace element 36 would therefore be in the position of use in case of an unexpected hurricane wind and also the brace element 36 would also minimize an unauthorized opening of the door. The operation of the alternate door construction 40 and the invention is substantially identical to the above-described operation of the door 10.

The embodiments of the invention in which an exclusive property or privilege is claimed are defined as follows:

We claim:

1. A brace device adapted to hold a door with respect to the structure defining the door opening, comprising: plural brace members secured to one side of said door and having surfaces spaced from said door and from each other, said brace members being substantially aligned in a direction extending between opposite edges of said door;

first anchor means secured to said structure near one edge of said door opening and being substantially in alignment with said brace members when said door is in a position closing said opening;

second anchor means secured to said structure near the opposite edge of said door opening and being substantially in alignment with said brace members; and

an elongated brace element connected to one of said anchor means and adapted for releasable connection to the other anchor means when said element is at least closely adjacent said edges of said brace members, whereby forces urging said door toward said brace element are absorbed by said structure.

2. A brace device according to claim 1, wherein said first anchor means is located near to, and spaced from the ends of, the upper edge of the door opening on the interior surface of said structure;

wherein said second anchor means is located near the lower edge of the door opening;

wherein said brace element is a flexible cable movably connected to said first anchor means; and

wherein said brace members are on the interior side of the door.

3. A brace device according to claim 2, and adapted for an upwardly acting door having a plurality of horizontally hinged sections movable between said closing position and a substantially horizontal position near the upper end of the door opening;

wherein at least one brace member is secured to each door section and extends lengthwise thereof spaced from the horizontal edges thereof, said brace members projecting from the interior side of the door.

4. A brace device according to claim 2, and adapted for an upwardly acting door having a plurality of horizontally hinged sections movable between said closing position and a substantially horizontal position near the upper end of the door opening;

wherein each door section has a plurality of horizontally spaced brace members disposed along the interior side thereof and projecting therefrom, each brace member on each section being substantially vertically aligned with brace members on other sections of said door; and

wherein there are plural first and second anchor means and plural brace elements engageable with said brace members.

5. The brace device as defined in claim 4, wherein each of said brace members extends horizontally along one of said sections and is at least 4 inches in length.

6. A brace device according to claim 2, including third anchor means mounted on said structure and spaced from said first anchor means for engagement by the lower end of said brace element, said third anchor means being above said door opening and arranged for storing

said brace element in a position spaced from said door opening.

7. The brace device as defined in claim 2, wherein said first and second anchor means are spaced frontwardly of said surfaces on said brace members.

8. A door reinforcing assembly comprising: a door, said door being track mounted for vertical operation;

a door frame having at least an upper cross member located adjacent the upper edge of said door when said door is in a closed position, and a base member located adjacent the lower edge of said door when said door is in a closed position;

an upper catch anchor mounted on said upper cross member and adapted to receive a portion of an upper catch;

a lower catch anchor mounted on said base member and adapted to receive a portion of a lower catch; tensioning means including elongated flexible element means engaged with one side of said door and extending between points near the upper and lower edges thereof;

an upper catch mounted on the upper end of said

tensioning means and having a portion thereof adapted to be received in said upper catch anchor; and

5 a lower catch mounted on the lower end of said tensioning means and having a portion thereof adapted to be received in locking relationship in said lower catch anchor.

10 9. A door reinforcing assembly as set forth in claim 8, in which said tensioning means includes a flexible cable and a plurality of brackets mounted on said door for spacedly supporting said cable from said door so that forces applied to said door are distributed to said door frame.
